UNITED STATES PATENT OFFICE.

WILLIAM L. MURPHY, OF CALEDONIA, MINNESOTA.

MAIL-BAG FASTENER.

Application filed May 16, 1924. Serial No. 713,835.

To all whom it may concern:

Be it known that I, WILLIAM L. MURPHY, a citizen of the United States, residing at Caledonia, in the county of Houston and State of Minnesota, have invented certain new and useful Improvements in Mail-Bag Fasteners, of which the following is a specification.

The present invention relates to mail bag fasteners and has for its prime object to provide a device of this nature possessed of an extremely simple and efficient structure, one which is reliable in operation, inexpensive to manufacture, durable, strong, and well adapted to the purpose for which it is designed.

With the above and numerous other objects in view as will appear as the description progresses, the invention resides in certain novel features of construction, and in the combination and arrangement of parts as will be hereinafter more fully described and claimed.

In the drawing:

Figure 1 is a perspective view of the fastener embodying the features of my invention,

Figure 2 is an elevation thereof the major portion being shown in section and substantially on the line 2—2 of Figure 1 looking in the direction of the arrows,

Figure 3 is an end elevation of the fastener, and

Figure 4 is a plan view thereof a portion of the hinged leaf being broken away.

Referring to the drawing in detail it will be seen that this fastener embodies a casing of box like structure formed by the walls indicated respectively by numerals 1, 2 and 3 and the ends 4 and 5. The wall 1 is shorter than the wall 3 and terminates a distance from end 4. End 4 is shorter than end 5 and its end is provided with a shelf 7 extending into the casing terminating just below the termination of wall 1. A leaf 8 has provided at one end a pair of apertured lugs 9 through which extend pins 10 which also pierce the walls 2 at their corners adjacent wall 1 and wall 4 so that this leaf is hingedly mounted on the casing. A rib or projection 11 is provided on the inner face of the leaf 8 above the shelf 7. The wall 1 is provided with an opening 12 through which the keeper 13 provided on the leaf 8

may pass through when positioned over the wall 1 as is indicated in Figure 2. The wall 1 is also provided with a keyhole opening 14. Any form of preferred or conventional lock is disposed in the casing adjacent wall 5 below the openings 15 provided therein for the operation of a bolt terminating in an eyelet 16 adapted to be moved in and out of engagement with the keeper 13. I have not shown the lock because any conventional lock may be used for this purpose and fastened into the casing and be operable by the key insertable through the keyhole 15. The ropes of a mail bag are passed through openings 15 of the end 5 over the shelf 7. The leaf 8 is then moved down on to wall 1 so that the rib 11 will bite into the ropes and hold them from moving longitudinally through the lock and thus the mail bag may be efficiently locked as will be understood by those familiar with their structure.

In order that an identification card may be held upon the fastener I provide the wall 3 thereof with the side angular flanges 20 and the end 4 with the stop 21. It will be so readily understood that a card may be slipped in between these flanges and wall 3 having thereon desirable identifying data.

It is thought that the construction and operation of this fastener will now be understood without any more detail description thereof. It is desired, however, to point out that numerous changes in the details of construction, and in the combination and arrangement of parts may be resorted to without departing from the spirit or scope of the invention as hereinafter claimed or sacrificing any of its advantages.

Having thus described my invention, what I claim as new is:

1. A fastener of the class described including a casing of a box like structure having one end provided with openings and the other end provided with an inwardly extending shelf, and an opening above the shelf, a leaf hinged in said last mentioned opening and provided with a rib adapted to engage ropes or the like passing through the openings first mentioned of one end of the casing when the leaf is closed down on the adjacent wall of the box like structure all in the manner and for the purpose specified.

2. A fastener of the class described including a casing having a box like structure including four walls and two ends, one end having openings therein and the other end
- 5 provided with an inwardly extending shelf, and an opening above the shelf, a leaf hinged in the opening to close thereover and provided with a rib for holding a rope in

engagement with the shelf, and means for holding the leaf in a closed position. 10

In testimony whereof I affix my signature in presence of two witnesses.

WILLIAM L. MURPHY.
